Carl Sopchack
By Jas. R. Dryden
Attorney

UNITED STATES PATENT OFFICE

CARL SOPCHACK, OF NEW KENSINGTON, PENNSYLVANIA

SEWING AWL

Application filed May 13, 1930. Serial No. 451,920.

My invention relates to certain new and useful improvements in sewing awls, and while primarily intended and designed for sewing meats by butchers, it will be obvious that the device may be employed for any other sewing operations and purposes wherein it is found to be applicable.

Important objects of the invention are to provide a sewing awl, of the character described, which will greatly facilitate meat sewing operations, which may be readily inserted into and withdrawn from the meat, and which embodies novel automatically operable means for retaining the sewing thread therein and the convenient removal of the latter therefrom.

Further objects of the invention are to provide a device of the class stated which is simple in its construction and arrangement, strong, durable and efficient in its use, and comparatively inexpensive to manufacture.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawing wherein like numerals of reference designate corresponding parts throughout the several views:—

Figure 1 is a side view of a sewing awl, constructed in accordance with the invention.

Figure 2 is a fragmentary side view of the needle member with the securing element removed therefrom.

Figure 3 is a fragmentary top plan view of my improved sewing awl.

Figure 4 is an enlarged plan view of the securing element while expanded prior to its assembly with the needle member.

Figure 5 is an enlarged end view of the securing element, illustrating its formation when assembled with the needle member.

Figures 6 and 7, are, respectively, fragmentary side and top plan views of a modified

form of needle member embodying the present invention.

Referring in detail to the drawing 1 denotes an elongated needle member having a flattened forward end portion 2 which terminates in a pointed piercing end 3. The rearward end of the needle member 1 carries a fixed operating handle 4 for facilitating the manipulation of the latter in effecting the sewing operations.

An angularly extending, open slot-eye 5 is formed in the flattened forward end portion 2, of the needle member 1. The closed end of the slot-eye 5 is preferably disposed forwardly, while the other end thereof opens at one side edge of the end portion 2.

The formation of the slot-eye 5, in the needle member 1, provides a forwardly disposed lip 6 and a rearwardly disposed shoulder 7 at the outer end of the slot-eye 5. The thickness of the shoulder 7 is reduced by providing each side thereof with a recess 8 for the reception of a securing element 9, which is pivotally mounted in a key-hole slot 10 formed in the shoulder 7 at the inner ends of the recesses 8.

The securing element 9 is substantially U-shaped and comprises a pair of flat side arms 11, which are joined together by an interposed, integrally formed, pivoting shaft 12. The securing element 9 is assembled with the needle member 1 by extending the latter through the key-hole slot 10, prior to its formation, as clearly shown in Figure 4, after which the side arms 11 thereof are bent upwardly, at right angles relatively to the pivoting shaft 12. The latter is mounted in the key-hole slot 10, while the side arms 11 are disposed in respective recesses 8. It is, of course, evident that the securing element 9 may be formed completely except one side arm thereof, as it is necessary to pass only one of said side arms through the key-hole slot 10 in the assembly of the device.

The thickness of each of the side arms 11 is exactly commensurate to the depth of the recess 8, in which it is mounted, and in consequence, when the securing element 9 is properly assembled with the needle member 1, as herein stated, the outer faces of the side

arms 11 will be disposed exactly flush with, or on the plane of the respective faces of the sides of the flattened end portion 2, as shown in Figure 3.

5 The outer end of each of the side arms 11 is formed to provide a tip 13, which projects slightly beyond the associated edge of the flattened portion 2, regardless of whether the securing element 9 is in the releasing position, 10 shown in Figure 1, or in the securing position, as shown in dash lines in Figure 1.

When in the releasing position, the side arms 11 of the securing element 9, are entirely disposed in respective recesses 8, and do 15 not extend into the slot-eye 5. When in the securing position, however, the side arms 11 extend across the slot-eye 5, to close the open outer end of the latter, and the tips 13 thereof abut and seat against the lip 6.

20 It will here be noted that the securing element 9 has a loose pivotal connection in the key-hole slot 10, whereby the former can shift to its securing or releasing positions by gravity. In practice, in forcing the needle member 1 through the meat, the latter will engage the securing element 9 and shift the same to the releasing position. This shiftable movement of the securing element 9 is of no importance and the insertion of the needle member 1 is not affected thereby.

However, when the needle member 1 is being withdrawn from the meat, after the sewing thread has been looped in the slot-eye 5 the securing member 9, by its frictional engagement with the meat will be forcibly shifted to and maintained in its securing position, thereby preventing the release of the sewing thread from the slot-eye 5 until the needle member 1 is entirely withdrawn from 35 the meat. The sewing thread may be then readily slipped from the eye-slot 5, for subsequent insertions of the needle member 1, as the securing member is loosely pivoted and will shift to release the sewing thread without 40 impeding the removal of the latter in any manner. The provision of the projecting tips 13 serves to augment the engagement of the meat with the securing element 9 for maintaining the latter in the securing position, and 45 facilitates the manipulation of the securing element 9 when looping the sewing thread in the slot-eye 5. Further, when the securing member 9 is in its securing position against the lip 6, the latter will not interfere with the 50 retraction of the needle member 1.

The modified form of the device, illustrated in Figure 6 and 7, differs from the preferred form hereinbefore described, in that a single securing arm 14 is employed instead of the securing element 9. The securing arm 14 is pivotally connected, as at 15, in a slot 16 formed in the flattened forward end 17, of the needle member 18. The function of the securing arm 14 is identical to that described 60 relatively to the preferred form, and is not

thought to require more detailed description.

It will be obvious, that the angular disposition of the slot-eye 5, may be reversed, so that the sewing action is effected during the insertion of the needle member instead of during its withdrawal movement, as provided for in the embodiment herein disclosed. 70

The present invention provides a most efficient device of its kind, which may be readily and smoothly inserted into meat or withdrawn from the latter, for effecting sewing operations, without any untoward retardation due to the position or movement of any parts of the device. 75

What I claim is:

1. In a sewing awl, of the character described, a needle member provided with a flattened forward end portion, a slot-eye formed in said flattened end portion and having an open outer end, said end portion being 80 formed with a pair of opposed recesses, a substantially U-shaped securing element pivotally connecting with said flattened end portion and including a pair of flat side arms respectively engaging in said recesses, said securing element being automatically operable 85 for shifting said pair of side arms to close the open outer end of said slot-eye. 90

2. In a sewing awl, of the character described, a needle member provided with a 95 flattened forward end portion, a slot-eye formed in said flattened end portion and having an open outer end, said end portion being formed with a pair of opposed recesses, a substantially U-shaped securing element pivotally connecting with said flattened end portion and including a pair of flat side arms respectively engaging in said recesses, said securing element being automatically operable 100 for shifting said pair of side arms to close the open outer end of said slot-eye, the outer ends of said pair of side arms including tips projecting beyond the adjacent side edge of 105 said needle member.

In testimony whereof I affix my signature. 110
CARL SOPCHACK.
